DIE FOR COLLAR PRESSING MACHINES

Stephen Stadub, Brooklyn, N. Y.

Application February 27, 1941, Serial No. 380,777

9 Claims. (Cl. 223—2)

My invention relates to dies for collar pressing machines and has particular reference to dies used in machines for pressing and shaping shirt collars.

In my United States Patents Nos. 2,141,051 and 2,222,447, I disclosed dies having collar supporting blocks with side walls extending above the block, the walls described in the Patent No. 2,222,447, being movable for pressing against the edges of a collar placed on the die block. I have found, however, that such a construction has a disadvantage in that it is difficult to maintain the edges of the die block and the side walls clean from particles of starch, lint, etc., which adhere to the surfaces from the collars.

My invention has for its object, therefore, to provide a die having a lower die block without any side walls, so that its surface can be easily kept clean. For pressing the edges of the collar I provide cylindrical members movably supported at the sides of the upper die block, the cylindrical members being pressed against the edges of the collar only when the upper block is lowered. The curvature of the cylindrical members facilitates their movement against the edges of the lower block.

Another object of my invention is to provide means to press the cylindrical members against the edges of the collar when the upper block is lowered and placed against the lower block. This is accomplished in my device by springs at the sides of the lower block, the springs engaging the lowered cylindrical members and pushing them against the edges of the lower block.

Still another object of my invention is to facilitate cleaning of the cylindrical members. I mount them for this purpose on shafts, so that the cylindrical members will present different portions of their surface to the edges of the collar and can be used for a long time without cleaning.

My invention is more fully described in the accompanying specification and drawing, in which:

Fig. 1 is a front view of my die with the upper block in a raised position partly in section;

Fig. 2 is a similar view with the upper block lowered;

Fig. 3 is a top plan view;

Figs. 4 and 5 are enlarged detail views of the die with the side rollers;

Fig. 6 is a bottom view of a modified die;

Fig. 7 is a detail view of another modification.

My collar pressing die consists of a base plate 1 supporting a lower die block 2 with an electric

heater 3 inside. The die block has sides converging at an angle corresponding to the angle of the point of a collar 5. The latter may be mounted on a thin flat die plate 6 by means of a suitable mechanism, such as is described, for instance, in my foregoing Patent No. 2,141,051. An upper die block 7 is provided with side extensions 8 mounted on vertical rods 9. Springs 10, resting on the base plate 1, support the upper block at an elevation above the lower block. The rods 9 are joined by a bar 11 connected by a rod 12 with a pedal 13. The upper block is lowered by manually depressing the pedal.

For pressing and shaping the edges and point 15 of the collar, rollers 14 are provided, rotatively mounted on rods or shafts 15 extending at the sides of the block. The inner ends of the shafts are pivoted on a pin 16, the outer ends being supported in brackets 17 with elongated slots 18 20 permitting certain freedom of movement of the shafts in the plane of the block. Springs 19 are mounted on the base 1 and press on the rollers 14, when the upper block is lowered, the pressure of the springs causing the rollers to press against 25 the edges of the collar.

The rollers converge at the converging end of the block, so that they can shape the collar to a fine point.

In order to enable the rollers to automatically 30 adjust themselves to the shape of the collar, they are mounted on the shafts with a certain clearance, the holes 20 being of a larger diameter than the shafts 15.

A modified device is shown in Fig. 6, shafts 21 35 being mounted at both ends in brackets 17 and 22 with elongated slots.

Another modification is shown in Fig. 7, the rollers being replaced by curved members 23 pivoted on shafts 24 and engaged by springs 19. The rounded sides of the rollers 14 or members 40 23 facilitate their movement at the edges of the lower block. The rollers can be rotated so that new and clean surfaces can be presented to the collar edges. The lower block can be easily kept 45 clean at all times, since it has no inside corners to gather dirt.

It is understood that my die for collar pressing machines may be further modified without departing from the spirit of the invention, as set forth in the appended claims.

I claim as my invention:

1. A die for collar pressing machines comprising a base plate, a lower die block on the plate having a flat top and sides converging together at an angle corresponding to the angle of a

shirt collar, an upper die block having a flat underside, means to support the upper block at an elevation above the lower block, means to move the upper block against the lower block for pressing a collar placed on the lower block, and members supported on side extensions of the upper block below its under side for pressing the edges of the collar.

2. A die for collar pressing machines comprising a base plate, a lower die block on the plate having a flat top and sides converging together at an angle corresponding to the angle of a shirt collar, an upper die block having a flat under side, means to support the upper block at an elevation above the lower block, means to move the upper block against the lower block for pressing a collar placed on the lower block, elongated members movably supported on side extensions of the upper block below its surface, and means to move the members into contact with the edges of the collar when the upper block is lowered.

3. A die for collar pressing machines comprising a base plate, a lower die block on the plate having a flat top and sides converging together at an angle corresponding to the angle of a shirt collar, an upper die block having a flat under side, means to support the upper block at an elevation above the lower block, means to move the upper block against the lower block for pressing a collar placed on the lower block, elongated members mounted on side extensions of the upper block and extending below its surface, and means at the sides of the lower block to move the members against the edges of the collar when the upper block is lowered.

4. A die for collar pressing machines comprising a base plate, a lower die block on the plate having a flat top and sides converging together at an angle corresponding to the angle of a shirt collar, an upper die block having side extensions and a flat under side, means to support the upper block at an elevation above the lower block, means to move the upper block against the lower block for pressing a collar placed on the lower block, elongated members movably mounted on the side extensions of the upper block, and yieldable means to press the members against the edges of the collar when the upper block is lowered.

5. A die for collar pressing machines comprising a base plate, a lower die block on the plate having a flat top and sides converging together at an angle corresponding to the angle of a shirt collar, an upper die block having side extensions and a flat under side and sides registering with the sides of the lower block, means to support the upper block at an elevation above the lower block, means to move the upper block against the lower block for pressing a collar placed on the lower block, elongated members pivotally supported on the extensions at the converging end of the upper block extending with their sides

below the upper block and adapted to engage the edges of the collar when the upper block is lowered, and means to move the members against the edges of the collar.

5 6. A die for collar pressing machines comprising a base plate, a lower die block on the plate having a flat top and sides converging together at an angle corresponding to the angle of a shirt collar, an upper die block having a flat under side, means to support the upper block at an elevation above the lower block, means to move the upper block against the lower block for pressing a collar placed on the lower block,

10 elongated members movably supported on extensions of the upper block and having cylindrical sides extending along the edges of the upper block, and means to cause the members to converge and to contact the edges of the collar when the upper block is lowered.

20 7. A die for collar pressing machines comprising a base plate, a lower die block on the plate having a flat top and sides converging together at an angle corresponding to the angle of a shirt collar, an upper die block having a flat under side, means to support the upper block at an elevation above the lower block, means to move the upper block against the lower block for pressing a collar placed on the lower block,

25 cylindrical members movably and rotatably supported at the sides of the upper block, and means to move the members against the edges of the collar placed on the lower block when the upper block is lowered.

30 8. A die for collar pressing machines comprising a base plate, a lower die block on the plate having a flat top and sides converging together at an angle corresponding to the angle of a shirt collar, an upper die block having a flat under side, means to support the upper block at an elevation above the lower block, means to move the upper block against the lower block for pressing a collar placed on the lower block,

35 cylindrical members rotatively supported on the shafts, and yieldable means to move the shafts with the members against the edges of the collar when the upper block is lowered.

40 9. A die for collar pressing machines comprising a base plate, a lower die block on the plate having a flat top and sides converging together at an angle corresponding to the angle of a shirt collar, an upper die block having a flat under side, means to support the upper block at an elevation above the lower block, means to move the upper block against the lower block for pressing a collar placed on the lower block,

45 shafts movably supported at the sides of the upper block, cylindrical members rotatively supported on the shafts, and resilient members at the sides of the lower block engaging the members and urging them against the edges of the collar when the upper block is lowered.

STEPHEN STADUE.
